EYELASH CURLER

Charles M. Palmer, Washington, D. C., assignor
to Adele Palmer, Brooklyn, N. Y.

Application March 30, 1948, Serial No. 18,040

19 Claims. (Cl. 132—32)

1

The subject matter of this invention is a functionally and structurally improved and serviceable eyelash curler wherein an arcuate fixed jaw is carried by spaced track means of a relatively stiff wire frame operatively sustaining a swingable actuator for bodily displacing a pair of complementary and adjustably coupled components defining a pad receiving movable jaw slidably guided by the spaced track means towards or away from the fixed jaw. In an eyelash curler of the type alluded to, one of the complements characterizes means to support the resilient pad while the other complement is utilized as a member for retaining and clamping the pad on and against the pad supporting complement. One important object of the invention resides in the provision of a conveniently operable movable jaw wherein a posterior pad supporting member or complement thereof is slidably guided by the track means and is hingedly connected to crank means of the swingable actuator and is characterized by an arcuate but vertical rim and an arcuate horizontal shelf or ledge and wherein an anterior clamping and retaining member or component is also hingedly connected to the crank means and embodies a rearwardly offset rim adapted when adjusted to engage the rubber pad mounted on the shelf in advance of the engagement of the lower and depending but separable aprons of the complements to positively position the rubber pad or filler against the rim of the supporting member against removal therefrom. Another object resides in the provision of a novel movably guided jaw comprising a pair of complementary removably nested components or complements embodying arcuate aprons having their lower terminals pivotally connected to crank means of the swingable actuator and having their breast portions desirably adjustably and removably coupled to permit adjustable displacement of one of the complements towards or away from the other complement of the pair to conveniently clamp or unclamp the rubber pad. Another object is to provide an improved movably guided jaw wherein the pad supporting complement thereof is characterized by spaced strengthening flanges between which the pad retaining and clamping complement is removably and adjustably received and nested upon the actuation of a knurled control wheel conveniently accessible at the front of the anterior pad retaining and clamping complement and carried by a stud fixedly sustained by the posterior pad sustaining complement and projecting through a clearance opening or elongated slot in the pad retaining and clamping comple-

2

ment. The invention has a further object to provide a slidably guided pad receiving receptacle wherein the front wall thereof is removed to allow for the insertion of the pad clamping closure means or anterior swingable complement conveniently adjustably controlled by coupling means accessible at the front part of the curler. Specifically the invention has as a further object the provision of a movable jaw comprising a pad supporting member having a shelf guided by the spaced track means of the wire frame and having a depending apron embodying a curved breast portion and a downwardly and rearwardly curved tail portion serving as fulcrum means having terminal means including spaced wings pivoted to and straddling the crank means of the swingable actuator, the movable jaw further comprising a pad retaining and clamping member having a depending apron including a downwardly and rearwardly curved tail portion for abutting the fulcrum means and having a breast portion spaced from the breast portion of the pad supporting member and adapted to be flexed towards the latter upon the manipulation of the adjustable control wheel carried by the pad supporting means and cooperating with the breast portion of the pad retaining and clamping member. The invention has as another object to preclude accidental displacement of the adjustable wheel by utilizing the compression of the rubber pad to react on the swingable retaining and clamping member for frictionally bearing against the adjustable wheel when the latter is clamping the retaining and clamping member against the rubber pad. The invention has as another object the provision of a movable jaw wherein both of its juxtaposed and depending aprons are pivotally connected to the posterior ends of the crank means of the actuator and wherein the anterior apron has a twisted portion for arranging a perforated terminal thereof substantially normal to the posterior apron to allow this terminal to be quickly inserted between juxtaposed parts of the crank means and permit swinging of the anterior apron towards or away from the posterior apron. Another object is to prevent accidental removal of the adjustable clamping wheel from the fixed stud or supporting means thereof carried by the posterior pad supporting complement. Another object resides in the provision of spaced lips forwardly offset relative to the vertical, resilient, upstanding and clamping arcuate rim of the swingable complement and fairly widely straddling the depending apron of the latter and adapted to abut the shelf or ledge serving as

stop means to limit adjustment of the swingable complement towards the rubber filler or pad. Another important object is realized in the provision of a normally swingable and arcuate component or member wherein the ends of the upper clamping and resilient rim thereof and its companion depending lips approach the rubber pad and the supporting shelf for the pad in advance of the arcuate intermediate or medial part of this normally contracted resilient but relatively rigid rim or bow which integrally embodies such ends, thus permitting on insertion of one or both ends of the rubber pad to be initially and quickly gripped by these ends to facilitate thereafter proper positioning of the pad within the receptacle after which the control knob or wheel is rotated to flex and flatten the bow or rim, thereby by expanding the curve of the medial part of the resilient rim whereby the latter as well as the now abutting ends thereof securely but disengageably grip and clamp the rubber pad in the receptacle of the supporting or sustaining complement of the movably guided jaw. Other salient objects and important functional and structural features of the invention will appear from the following detailed description considered in the light of the accompanying drawings wherein:

Fig. 1 is a front view of the eyelash curler according to my invention, illustrating the curler closed.

Fig. 7 is a fragmentary perspective view of the curler illustrating the wire frame pivotally sustaining the swingable lever for actuating the slidably guided jaw.

Fig. 8 is a vertical transverse sectional view on the line 8—8 of Fig. 1 but showing the curler opened.

Fig. 9 is a vertical transverse sectional view similar to Fig. 8 showing the curler closed and crimping an eyelash between the fixed jaw and the pad or filler removably clamped by the movable jaw.

Fig. 10 is a horizontal sectional view on the line 10—10 of Fig. 8.

Fig. 11 is a fragmentary enlarged vertical sectional view of the movable jaw showing the rotatable and swingable complement thereof widely separated but still coupled to its companion complement or pad sustaining member, this view may also be said to be a fragmentary view of Fig. 8 with the complements of the movable jaw opened.

Fig. 12 is a fragmentary enlarged view of Fig. 11 however illustrating the swingable complement of the movable jaw just engaging the rubber pad prior to clamping the latter against the relatively rigid vertical but arcuate upper guard

or rim of the slidably guided pad sustaining member.

Fig. 13 is a view along the lines of Fig. 12 depicting the removable rubber pad however firmly clamped and slightly compressed between the upper guard or rim of the rear slidable or posterior pad sustaining member and the front or proximal adjustable and rotatable pad retaining member of the movable or shiftable jaw.

Fig. 13A is a sectional view on the line 13A—13A of Fig. 13.

Fig. 14 is a view taken on the line 14—14 of Fig. 12 to illustrate the relief or clearing opening or slot of the forwardly projecting boss of the hinged and rotatable clamping component of the movable jaw.

Fig. 15 is a view similar to Fig. 13 showing the movable jaw closed but empty of a rubber pad.

Fig. 16 is a view similar to Fig. 3 however illustrating the ends or terminals only of the relatively rigid but resilient and normally contracted rim of the swingable clamping component abutting the ends of the rubber pad to hold the latter in position within the receptacle at which time the medial arcuate portion of this rim is spaced and unclamped from the pad.

Fig. 17 is a fragmentary perspective view of the slidable jaw however with the stud thereof of the type shown in Figs. 11 and 16 but not upset and completely uncoupled from the swingable pad retaining member or complement of the movable jaw.

Fig. 18 is a fragmentary view of Fig. 1 however with the movable jaw in the relation shown in Fig. 16 permitting the pad to be quickly gripped at one end thereof prior to positioning within the receptacle and prior to final clamping.

Fig. 19 is a plan view of Fig. 18 illustrating the pad in a bias relation and having one end gripped by the resilient but adequately rigid rim of the swingable complement, and

Fig. 20 is a fragmentary transverse and enlarged sectional view on the line 20—20 of Fig. 1.

Illustrative of the embodiment disclosed, the movable jaw generally denoted MJ (Fig. 17) comprises a pad supporting member or component PS and a swingable pad retaining and clamping member RM, each preferably of suitable sheet metal.

The pad supporting member PS embodies an arcuate forwardly projecting lower shelf or ledge 11 provided at its ends with the spaced openings 12 in part surrounded by the upstanding bearings 13.

Bent downwardly from and integral with the forward edge or margin of shelf 11 is the depending channel shaped and tapered apron broadly denoted 14 (Figs. 6, 12 and 17) appropriately countersunk to provide the forwardly projecting hollow boss 15. Apron 14 may be said to be flared having its widest part or breast portion 16 (Fig. 17) merging with the arcuate shelf 11. The tail portion 17 of the apron 14 curves downwardly and rearwardly and merges with the forwardly projecting substantially parallel and spaced perforated ears or wings 18 defining the clearance slot 19.

Of importance in the matter of providing rigidity and strength to the tapered sheet metal apron 14 are the spaced and appreciably forwardly projecting flanges 20 integral with and arranged along the sides of the breast and tail portions 16 and 17 of the apron 14. By such construction the apron 14 may be said to be reinforced but channelled (Fig. 4) for telescopically receiving

70 75

and closely but removably straddling the swingable sheet metal retaining and clamping member RM and by such arrangement the latter is also positioned and guided towards or away from the apron 14 and is precluded from lateral displacement relative thereto.

Since the forward ends of the bearings 13 (Figs. 3A and 17) are appreciably spaced apart they provide a suitable gateway G for convenient insertion of the rubber pad or filler R on the shelf 11 having its openings 12 slidably receiving the spaced upstanding sides or tracks 21 of the relatively rigid one piece metal wire frame broadly designated F (Fig. 7) having the downwardly converging branches 22 in turn merging with the spaced flattened portions or bearings 23 merging with the handle generally designated H comprising juxtapositioned reaches 24 defining the finger receiving loop 25. At the upper ends of the upstanding portions or sides 21 the arcuate stationary sheet metal bar or jaw J is appropriately fixed or anchored.

For actuating the pad sustaining member PS towards or away from the fixed arcuate jaw or brace J the flattened rearwardly extending crank portions 26 of the juxtapositioned and offset reaches 27 of the swingable one piece metal wire lever L are first interposed between the flattened and spaced bearings 23 of the frame F and are pivoted on the front fulcrum rivet or pin 28 carried by the bearings 23. To facilitate such shifting of the pivoted lever L the reaches 27 are integrally merged with the finger receiving loop 29. With the crank portions 26 pivotally sustained by the frame F they extend rearwardly thereof as shown and are closely but movably straddled by the spaced ears 18 of the pad sustaining member PS. The fulcrum pin 30 carried by the outer perforated ends of the crank portions 26 is appropriately upset to pivotally retain the ears 18 relative to the lever L.

However prior to insertion of the fulcrum pin or rivet 30 into the aligned perforations 31 and 32' (Figs. 5 and 10) of the ears 18 of the pad sustaining member PS and crank portions 26 of the pivoted hinged lever or actuator means L, the lower terminal or ear 32 of the pad retaining and clamping member RM is first interposed between the rear ends of the crank portions 26. Ear 32 is provided with an opening 33 (Fig. 10) adapted to line up with the aligned perforations 31 and 32' of the pivoted ears 18 and the crank portions 26 after which the fulcrum pin 30 or axis for the clamping and retaining complement RM is inserted and upset. By this arrangement, ear or lug 32 of the pad retaining and clamping member RM and the ears or wings 18 of the pad sustaining member PS are pivotally sustained by the fulcrum pin or axis 30. Or in other words the axis of rotation of the clamping and retaining member or component RM in the matter of swinging the latter towards or away from the companion pad supporting complement PS is approximately or almost normal to the vertical axis of the spaced sides or tracks 21.

The pad retaining clamping member RM has an upper arcuate margin, rim or guard 35 from which integrally extends the forwardly projecting arcuate flange, shoulder or ledge 36 and integral with the latter and depending and bent down from the forward part thereof is the sustained front or proximal and tapered apron 37 (Fig. 1) characterized by an upper and relatively wide breast portion 38 and a lower downwardly contracted tail portion 39. The breast portion 38

is provided with the forwardly struck out boss 40 having the outside flat face 41 (Figs. 12 and 14) which is interrupted by the elongated vertical relief or clearing opening or slot 42. The arcuate tail portion 39 of the swingable apron 37 is provided near the lower end with the twist 43 to arrange the perforated ear or lug 32 substantially normal to the tail portion 39.

By the arrangement disclosed, the retaining and clamping member or swingable complement RM of the movable jaw MJ may be swung bodily about the fulcrum or hinge pin 30 towards or away from the channeled apron 14 of the pad sustaining member PS whereby the upper arcuate wall or rim 35 may be removably received between the bearings 13 and into or out of the gateway G. Also the proximal or front apron 37 is swingable into and out of the posterior channeled apron 14 and is adapted to be removably nested therein. Suitably fixedly anchored against rotation in the breast portion 16 of the depending apron 14 of the slidably guided pad sustaining member or complement PS is the forwardly projecting and exteriorly threaded stud 44 on which the internally threaded manipulatable and rotatable knurled wheel 45 is mounted, the wheel being limited in its displacement away from the movable jaw MJ by the enlarged stop shoulder 46 on stud 44. The stud 44 projects through the elongated relief or clearing slot 42 in the boss 40 of the swingable component RM to permit the latter ample divergence or spread for convenient mounting of the rubber pad or filler R onto the shelf or support 11 of the pad sustaining member PS as indicated in Fig. 11. In such position the rotatable wheel 45 is against stop 46 and component RM is widely displaced from its companion complement PS, the boss 40 cooperating with wheel 45 to limit divergence of complement RM away from the complement PS. In this relation the movable jaw MJ may be said to be fully opened but still coupled to the external threaded stud 44.

Pursuant to positioning of the rubber pad R on shelf 11, wheel 45 is rotated by the fingers of the operator, thus automatically shifting or actuating the swingable complement RM in a direction towards the complement PS. During such operation the flat face 47 (Fig. 12) of the wheel 45 cooperates with the flat face 41 of the boss 40. On closing of the swingable jaw MJ, arcuate tail portion 39 of apron 37 thereof is telescopically received by the correspondingly curved tail portion 17 of the apron 14. Or in other words, the swingable component RM is nested in part within rear apron 14 and between the strengthening flanges 20 thereof. Ultimately front tail portion 39 contacts the rear tail portion 17 but only after the upstanding arcuate rim or guard 35 has engaged in a manner hereinafter more particularly described the rubber pad R (Fig. 12) for urging and holding this pad against the rear arcuate guard or rim 10. As the accessible manipulating wheel is further rotated in the same direction, the front breast portion 38 flexes towards the rear breast portion 16, consequently shifting the offset flange or shoulder 36 slightly above ledge 11, thereby reducing the distance between the upper rims 10 and 35 whereby the clamping rim 35 compresses the rubber pad against the rear rim 10, thereby firmly clamping the pad against removal. In such relation the movably guided jaw MJ may be said to be closed but clamping the pad firmly. The rearwardly and downwardly curved pos-

terior tail portion 17 may also be considered as a seat or fulcrum means for the substantially correspondingly curved anterior or front tail portion 39 to permit the upper breast portion 38 to swing or flex towards the posterior breast portion 17 on tightening of the wheel, or in other words, the upper breast portion 38 is integrally hinged to its companion and depending tail portion 39.

While the pad is held in a compressed and clamped relation as shown in Fig. 13, the pad now has a tendency to urge rim or bow 35 outwardly, hence causing an outward thrust on the boss 40, and consequently the latter is maintained in its set frictional engagement with the wheel 45, thereby precluding accidental rotation of the latter.

If the wheel be rotated to shift in a direction towards stop 46, that is, away from the pad support component or member PS, the pad R expands and automatically shifts rim 35 away from the rim 10, and even ledge or shoulder 36 away from seat or shelf 11. Thereafter the swingable or rotatable retaining and clamping member or component RM may be further tilted forwardly to appreciably diverge it away from member PS or in other words, the movable jaw MJ is again opened to permit quick removal of the pad or filler R and cleaning of the curler and this pad. It follows that the pad may be readily again inserted in the movable jaw and subsequently clamped in a compressed relation. In the fully opened relation of the curler as shown in Fig. 11, the stop 46 prevents removal of the manipulating wheel from the threaded stud 44. It is also apparent that the elongated slot 42 in the boss 40 of the clamping and retaining rotatable member RM permits the latter to swing appreciably about the threaded stud 44.

Of course the curved rims 10 and 35 together with shelf 11 constitute a receptacle for retaining the pad R while the anterior rim 35 may be considered as a closure for one side of the receptacle of which the channeled apron or fulcrum means 14 is a depending part. As is well appreciated, the rims 10 and 35, and jaw J are so curved as to permit convenient crimping of eyelashes as E when interposed between the rubber pad R and the fixed jaw or bar J.

By tilting lever L away from handle H, cranks 26 simultaneously drive the slidably guided jaw MJ downwardly until bearings 13 hit the curved portions or elbows 49. The eyelash curler is now fully opened to allow convenient insertion of the eyelashes to be crimped between the rubber or resilient pad and the fixed jaw. Thereafter the pivoted lever L is tilted towards the handle H. This action causes cranks 26 to elevate the fulcrum pin 30. Consequently wings 18 of component 14 and the perforated lug or terminal 32 of the swingable component or member RM are swung or arcuately displaced upwardly, thereby bodily actuating the movable jaw, the components PS and RM of which are desirably coupled together by the threaded stud 44 and the internally threaded wheel 45 thereon. When the pad R directs the eyelashes against the upper fixed arcuate brace or jaw J (Fig. 9), lever or acuator means L is held depressed until the eyelashes are desirably crimped or curled. Usually this takes place in a few seconds after which the curler is again opened to remove the crimped lashes.

As previously stated, the stud 44 is fixedly and non-rotatably anchored to the posterior apron

14 of the movable jaw MJ. In this connection stud 44 is provided with a reduced squared portion 60 (Figs. 13 and 13A) fitting into a corresponding cross sectionally shaped opening 61 in boss 15 to preclude rotation. With the stud so positioned against rotation, the stud 44 is upset to provide the enlarged head 62 disposed within the countersunk boss 15. The head 62 together with the body of stud 44 closely straddle boss 15, thus precluding removal of the stud from the apron 14.

Concerning the elastic or rubber pad R (Fig. 3B) the latter is oblong and when removably clamped extends slightly above the curved rims or guards 10 and 35.

In Figs. 3A, 16, and 19, jaw MJ is open. The shoulder 36 while adapted to removably seat itself on ledge 11 at the transverse axial plane of the curler (that is, along the line 8-8 of Fig. 1) nevertheless progressively clears this ledge in proportion to the distance away from line 8-8 to permit the spaced lips 70 forwardly offset relative to rim 35 and depending from shoulder 36 to extend appreciably below shelf 11 which limits inward movement of the swingable component RM when struck by lips 70 (Fig. 20).

Of importance however is the fact that rim 35, shoulder 36, and the depending spaced lips 70 are not concentrically disposed relative to the rear of posterior rim 10 and normally the terminals or ends 71 of the upper rim and also the corresponding ends of the spaced lips 70 "toe in" relative to seat or shelf 11. Or in other words, lips 70 reach the rubber pad (Figs. 16 and 19) in advance of the center part of the rim 35. By this arrangement, the movable jaw need be opened just slightly for first positioning and thereafter seating the pad therein. With the movable jaw open (Fig. 3A), the operator places the thumb of one of his hands at the back of and against one of the depending lips 70 and urges the latter outwardly away from the rear rim 10. By this action terminal 71, above the lip 70 so displaced, moves in a similar direction thereby at this location widening the distance between rims 10 and 35 whereby one end or terminal of the pad (Fig. 18) may be readily dropped onto shelf 11. The operator now removes his thumb from the lip actuated. Immediately this end of the rim 35 automatically retracts due to its own resiliency to firmly grip the end of the pad now in the receptacle (Figs. 18 and 19). Thereafter the other end or terminal 73 of the pad is quickly inserted into the receptacle or onto shelf 11 (Fig. 16) and becomes automatically and firmly gripped. At this time the ends 71 only of the rim 35 (Figs. 16 and 20) and the outer ends of the depending and offset lips 70 are yieldingly abutting the ends of the pad while the intermediate portion of the rim 35 between the ends 71 is spaced from the pad.

The wheel 45 is now actuated, causing the front apron 31 to swing towards the rear apron 14 ultimately causing tail portion 39 to strike and bear against the rear tail or fulcrum portion 17. Upon further rotation of the control wheel in the same direction the breast part 38 of the swingable component RM is flexed towards the rear breast portion 16 and the rim 35 is deformed, partly collapsed, or expanded to fully grip pad R (Fig. 3). In the position of the pad in Fig. 16 the curler may be held closed by shifting actuator means or lever L towards handle H. By such action the central part of the pad is maintained fully seated on shelf 11 after which the wheel is tightened to

deform rim 35 to fully grip and clamp the pad in its fully seated position.

To remove the pad from the movable jaw MJ, the control wheel or member is loosened. This action automatically contracts rim 35 causing the central part thereof to move away from the central part of the pad and by applying an outward gripping thrust on the latter the pad thereafter is conveniently lifted or withdrawn from the receptacle.

For purposes of specification the resilient and flexible rim or bowed portion 35 may be said to be normally contracted and adapted to be deformed or flattened slightly upon operation of the control wheel all of course when the rubber pad is within the receptacle and having its ends or terminals gripped by the "offset, or toed in" ends disposed in advance of the intermediate part of rim 35.

In Fig. 13, the rubber pad R is firmly clamped in the movable jaw and so held. Upon loosening of the wheel 45, the breast portion 38 although urged outwardly by the expansion of the pad, also automatically retracts, due to its own resiliency, to its normal unflexed relation upon further loosening of the wheel. In actual practice once the clamping pressure on the pad is removed, the pad may be quickly withdrawn from the curler and thereafter a new pad if desired conveniently substituted. It is not necessary to widely open the movable jaw for such purpose and only a few turns of this wheel is required to remove the clamping relation. Thus by the present invention the pad may be quickly removed, cleaned and again inserted into the movable jaw. Or the old and used pad may be replaced by a new one, as previously pointed out.

According to the invention it is apparent that the depending ear 32 of the front apron is rotatably retained between the outer ends or guide means of crank portions 26 on the fulcrum pin 30 which also pivotally or hingedly sustains wings 18 of the rear apron 14. By such an arrangement both aprons 14 and 37 are pivotally or hingedly associated with the actuating means or lever L and of course in moving the clamping member RM towards seat or shelf 11, that is in closing of the member RM the toed in ends 71 always reach the latter in advance of the retaining intermediate arcuate part of the collapsible rim or bowed portion 35 as previously stated. On closing of member RM spaced notches 74 thereof removably receive the upper ends of the strengthening flanges 20 (Fig. 18).

By first gripping one end of the pad R (Figs. 18 and 19) and thereafter gripping the other end thereof (Fig. 16), the pad may be quickly positioned and seated on shelf 11 without danger of the pad falling out of the receptacle before full clamping thereof and it will be observed that as the ends of lips 70 reach the pad they also serve to clamp and retain the latter against the posterior rim 19 (Fig. 6).

The present application is a continuation in part of my copending application S. N. 705,526, filed October 25, 1946, now abandoned.

Various changes may be made in details of construction and arrangement of parts without departing from the spirit of the invention or sacrificing any of the advantages thereof inherent therein.

I claim:

1. An eyelash curler adapted to utilize a rubber pad, comprising; a frame, an arcuate brace secured to said frame, an actuator movably carried

by said frame, a jaw disposed below said brace having an arcuate pad sustaining member and an arcuate pad retaining member disposed in advance of said pad sustaining member, means hingedly connecting said pad sustaining member to said actuator, means rotatably connecting said pad retaining member to said actuator, means for slidably guiding said pad sustaining member relative to said frame, and adjustable means for rotatably displacing said pad retaining member towards said pad sustaining member to removably clamp said pad in said jaw.

2. An eyelash curler adapted to utilize a rubber pad, comprising; a frame, an arcuate brace secured to said frame, an actuator movably carried by said frame, a jaw disposed below said brace having a channeled pad sustaining member and a pad retaining member disposed in advance of said pad sustaining member and in part removably receivable in said pad sustaining member, means hingedly connecting said pad sustaining member to said actuator, means rotatably connecting said pad retaining member to said actuator, means for slidably guiding said pad sustaining member relative to said frame, and adjustable means for rotatably displacing said pad retaining member towards said pad sustaining member to removably clamp said pad in said jaw.

3. An eyelash curler adapted to utilize a rubber pad, comprising; a frame, an arcuate brace secured to said frame, an actuator movably carried by said frame, a jaw disposed below said brace having a pad sustaining member provided with spaced forwardly extending flanges and having a pad retaining member disposed in advance of said pad sustaining member and removably receivable between said flanges, means hingedly connecting said pad sustaining member to said actuator, means rotatably connecting said pad retaining member to said actuator, means for slidably guiding said pad sustaining member relative to said frame, and adjustable means for rotatably displacing said pad retaining member towards said pad sustaining member to removably clamp said pad in said jaw.

4. An eyelash curler adapted to utilize a rubber pad, comprising; a frame, an arcuate brace secured to said frame, an actuator movably carried by said frame, a jaw disposed below said brace and having an arcuate pad sustaining member and an arcuate pad retaining member disposed in advance of said pad sustaining member, said pad sustaining member comprising an arcuate shelf for supporting said pad, an arcuate guard for maintaining said pad on said shelf, and an apron depending from said shelf; said pad retaining member comprising an upper arcuate rim and a depending apron, means hingedly connecting the apron of said pad sustaining member to said actuator, means rotatably connecting the apron of said retaining member to said actuator, means for slidably guiding said pad sustaining member relative to said frame, and adjustable means coupling said aprons for rotatably displacing said pad retaining member towards said pad sustaining member to shift said rim towards and against said pad to removably clamp the latter against said guard.

5. An eyelash curler adapted to utilize a rubber pad, comprising; a frame, an arcuate brace secured to said frame, an actuator movably carried by said frame, a jaw disposed below said brace having an arcuate pad sustaining member and an arcuate pad retaining member disposed in advance of said pad sustaining member, said pad

sustaining member comprising an arcuate shelf for supporting said pad, an arcuate guard for maintaining said pad on said shelf, an apron depending from said shelf comprising spaced stiffening means; said pad retaining member comprising an upper arcuate rim and a depending apron removably receivable between said stiffening means, means hingedly connecting the apron of said pad sustaining member to said actuator, means rotatably connecting the apron of said retaining member to said actuator, means for slidably guiding said pad sustaining member relative to said frame, and adjustable means coupling said aprons for rotatably displacing said pad retaining member towards said pad sustaining member to shift said rim towards and against said pad to removably clamp the latter against said guard.

6. An eyelash curler adapted to utilize a rubber pad, comprising; a frame, an arcuate brace secured to said frame, an actuator movably carried by said frame, a jaw disposed below said brace having an arcuate pad sustaining member and an arcuate pad retaining member disposed in advance of said pad sustaining member, said pad sustaining member comprising an arcuate shelf for supporting said pad, an arcuate guard for maintaining said pad on said shelf, and an apron depending from said shelf; said pad retaining member comprising an upper arcuate rim, an arcuate shoulder extending forwardly of said rim, and an apron depending from the forward part of said shoulder; means hingedly connecting the apron of said pad sustaining member to said actuator, means rotatably connecting the apron of said retaining member to said actuator, means for slidably guiding said pad sustaining member relative to said frame, and adjustable means coupling said aprons for rotatably displacing said pad retaining member towards said pad sustaining member to shift said shoulder on said shelf and said rim towards and against said pad to removably clamp the latter against said guard.

7. An eyelash curler adapted to utilize a rubber pad, comprising; a frame, an arcuate brace secured to said frame, an actuator movably carried by said frame and having crank portions disposed rearwardly of said frame, a jaw disposed below said brace having an arcuate pad sustaining member and an arcuate pad retaining member disposed in advance of said pad sustaining member, said pad sustaining member comprising an arcuate shelf for supporting said pad, an arcuate upstanding guard for maintaining said pad on said shelf, an apron depending from the forward part of said shelf and having spaced perforated wings straddling said crank portions; said pad retaining member comprising an upper upstanding arcuate rim, a depending apron, and a perforated terminal; fulcrum means traversing said wings and terminal and retained at the rear parts of said crank portions for hingedly sustaining said wings and rotatably sustaining said terminal, means for slidably guiding said pad sustaining member relative to said frame, and adjustable means coupling said aprons for rotatably displacing said pad retaining member towards said pad sustaining member to shift said rim towards and against said pad to removably clamp the latter against said guard.

8. An eyelash curler adapted to utilize a rubber pad, comprising; a frame, an arcuate brace secured to said frame, an actuator movably carried by said frame and having crank portions disposed rearwardly of said frame, a jaw disposed

below said brace having an arcuate pad sustaining member and an arcuate pad retaining member disposed in advance of said pad sustaining member, said pad sustaining member comprising an arcuate shelf for supporting said pad, an arcuate upstanding guard for maintaining said pad on said shelf, an apron depending from the forward part of said shelf, and having spaced perforated wings straddling said crank portions; said pad retaining member comprising an upper upstanding arcuate rim, a depending apron offset relative to said rim and provided with a clearing opening and having a perforated terminal interposed between said crank portions; fulcrum means traversing said wings and terminal and retained at the rear parts of said crank portion for hingedly sustaining said wings and rotatably sustaining said terminal, means for slidably guiding said pad sustaining member relative to said frame, a threaded stud fixed to said pad sustaining member and projecting forwardly thereof into said opening, and means on said stud for shifting said pad retaining member to removably clamp said rim against said pad.

9. An eyelash curler adapted to utilize a rubber pad, comprising; a frame, an arcuate brace secured to said frame, an actuator movably carried by said frame and having crank portions disposed rearwardly of said frame, a jaw disposed below said brace having an arcuate pad sustaining member and an arcuate pad retaining member disposed in advance of said pad sustaining member, said pad sustaining member comprising an arcuate shelf for supporting said pad, an arcuate upstanding guard for maintaining said pad on said shelf, a downwardly and rearwardly curved apron depending from the forward part of said shelf and having spaced perforated wings straddling said crank portions; said pad retaining member comprising an upper upstanding arcuate rim, a depending downwardly and rearwardly curved apron integral with said rim and in part offset forwardly relative thereto and provided with a clearing opening and having a perforated terminal substantially normal to said rim and interposed between said crank portions; fulcrum means traversing said wings and terminal and retained at the rear parts of said crank portions for hingedly sustaining said wings and rotatably sustaining said terminal, means for slidably guiding said pad sustaining member relative to said frame, a threaded stud fixed to said pad sustaining member and projecting forwardly thereof into said opening, and means on said stud for shifting said pad retaining member towards said pad to removably clamp said rim against said pad.

10. An eyelash curler adapted to utilize a rubber pad, comprising; a frame, an arcuate brace secured to said frame, an actuator movably carried by said frame and having crank portions disposed rearwardly of said frame, a jaw disposed below said brace having an arcuate pad sustaining member and an arcuate pad retaining member disposed in advance of said pad sustaining member, said pad sustaining member comprising an arcuate shelf for supporting said pad, an arcuate upstanding guard for maintaining said pad on said shelf, an apron provided with a boss and depending from the forward part of said shelf and having spaced perforated wings straddling said crank portions; said pad retaining member comprising an upper upstanding arcuate rim, a depending apron offset in part forwardly of said rim and having a boss embodying

a clearing opening and having a perforated terminal interposed between said crank portions; fulcrum means traversing said wings and terminal and retained at the rear parts of said crank portions for hingedly sustaining said wings and rotatably sustaining said terminal, a threaded stud non-rotatably carried by said first mentioned boss and projecting into said opening, and means on said stud for shifting said second mentioned boss to removably clamp said rim against said pad.

11. An eyelash curler adapted to utilize a rubber pad, comprising; a frame, an arcuate brace secured to said frame, an actuator movably carried by said frame, a jaw disposed below said brace having a rear arcuate pad sustaining member and a front arcuate pad retaining member, said pad sustaining member comprising an arcuate shelf for supporting said pad, an arcuate upstanding guard for maintaining said pad on said shelf, and an apron depending from said shelf having a relatively wide upper breast portion and lower downwardly and rearwardly curved tail portion; said pad retaining member comprising an upper arcuate rim and a depending apron having a relatively wide upper breast portion and a downwardly and rearwardly curved tail portion, means hingedly connecting the tail portion of the apron of said pad sustaining member to said actuator, means rotatably connecting the tail portion of the apron of said pad retaining member to said actuator, means for slidably guiding said pad sustaining member relative to said frame, and adjustable means coupling said aprons for rotatably displacing said pad retaining member towards said pad sustaining member to initially shift said rim towards and against said pad and for subsequently abutting the tail portion of said retaining member against the aforementioned tail portion of said sustaining member and for thereafter flexing the breast portion of said retaining member towards the breast portion of said sustaining member for removably clamping said rim against said pad.

12. An eyelash curler adapted to utilize a rubber pad, comprising; a frame, an arcuate brace secured to said frame, an actuator movably carried by said frame, a jaw disposed below said brace having an arcuate pad sustaining member and an arcuate pad retaining member disposed in advance of said pad sustaining member, said pad sustaining member comprising an arcuate shelf for supporting said pad, an arcuate guard for maintaining said pad on said shelf, and an apron depending from said shelf having a relatively wide upper breast portion and lower downwardly and rearwardly curved tail portion; said pad retaining member comprising an upper arcuate rim and a depending apron having a relatively wide upper breast portion including a clearing opening and a downwardly and rearwardly curved tail portion, means hingedly connecting the tail portion of the apron of said pad sustaining member to said actuator, means rotatably connecting the tail portion of the apron of said retaining member to said actuator, means for slidably guiding said pad sustaining member relative to said frame, threaded means fixed to said pad sustaining member and projecting through said opening, and means mounted on said stud for rotatably displacing said pad retaining member towards said pad sustaining member to initially shift said rim towards and against said pad and for subsequently abutting the tail portion of said retaining member against the aforementioned

tail portion of said sustaining member and for thereafter flexing the breast portion of said retaining member towards the breast portion of said sustaining member for removably clamping said rim against said pad.

13. An eyelash curler adapted to utilize a rubber pad, comprising; a frame, an arcuate brace secured to said frame, an actuator movably carried by said frame, a jaw disposed below said brace having an arcuate pad sustaining member and an arcuate pad retaining member disposed in advance of said pad sustaining member, said pad sustaining member comprising an arcuate shelf for supporting said pad, an arcuate guard for maintaining said pad on said shelf, and an apron depending from said shelf having a relatively wide upper breast portion including a boss and having a lower downwardly and rearwardly curved tail portion; said pad retaining member comprising an upper arcuate rim and a depending apron having a relatively wide breast portion including a boss provided with a clearing opening and having a downwardly and rearwardly curved tail portion, means hingedly connecting the tail portion of the apron of said pad sustaining member to said actuator, means rotatably connecting the tail portion of the apron of said retaining member to said actuator, means for slidably guiding said pad sustaining member relative to said frame, threaded means fixed to said first mentioned boss and projecting through said opening, and means mounted on said stud for rotatably displacing said pad retaining member toward said pad sustaining member to initially shift said rim towards and against said pad and to subsequently abut the tail portion of said retaining member against the aforementioned tail portion of said sustaining member and for thereafter flexing the breast portion of said retaining member towards the breast portion of said sustaining member for removably clamping said pad.

14. An eyelash curler adapted to utilize a rubber pad, comprising; a frame, an arcuate brace secured to said frame, an actuator movably carried by said frame, a jaw disposed below said brace having an arcuate pad sustaining member and an arcuate pad retaining member disposed in advance of said pad sustaining member, said pad sustaining member comprising an arcuate shelf for supporting said pad, an arcuate guard for maintaining said pad on said shelf, and an apron depending from said shelf having a relatively wide upper breast portion and a lower downwardly and rearwardly curved tail portion defining fulcrum means and provided with spaced stiffening means; said pad retaining member comprising an upper arcuate rim and a depending apron integral with and offset forwardly of said rim and having a relatively wide upper breast portion and a downwardly and rearwardly curved tail portion for abutting said fulcrum means, means hingedly connecting the tail portion of the apron of said sustaining member to said actuator, means rotatably connecting the tail portion of the apron of said retaining member to said actuator, means for slidably guiding said pad sustaining member relative to said frame, and adjustable means coupling said aprons for rotatably displacing said pad retaining member towards said pad sustaining member to initially shift said rim towards and against said pad and for subsequently abutting the tail portion of said retaining member against said fulcrum means and for thereafter flexing the breast portion of said retaining member towards the breast portion of said

15

sustaining member for removably clamping said rim against said pad.

15. An eyelash curler adapted to utilize a rubber pad, comprising; a frame, an arcuate brace secured to said frame, an actuator movably carried by said frame, a jaw disposed below said brace and comprising a pair of cooperating components, one of said components defining a pad sustaining member and the other component of said pair defining a pad retaining member disposed in advance of said pad sustaining member and having a clearing opening, means hingedly connecting said pad sustaining member to said actuator, means rotatably connecting said pad retaining member to said actuator, means for slidably guiding said pad sustaining member relative to said frame, a threaded stud carried by one of said components and projectable forwardly through said opening, an internally threaded wheel mounted on said stud for actuating said pad retaining member to removably clamp said pad in said movable jaw, and stop means on said stud to limit the displacement of said wheel away from said pad retaining member.

16. An eyelash curler adapted to utilize a rubber pad, comprising; a frame, an arcuate brace secured to said frame, an actuator movably carried by said frame, an arcuate jaw disposed below said brace and comprising a pair of cooperating components, one of said components defining a pad sustaining member including a shelf for seating said pad and an upstanding arcuate rim, the other component of said pair defining a pad retaining member including an upstanding arcuate portion disposed in advance of said pad sustaining member and having a depending portion embodying a clearing opening, means hingedly connecting said pad sustaining member to said actuator, means rotatably connecting said pad retaining member to said actuator, means slidably guiding said pad sustaining member relative to said frame, a threaded stud carried by one of said components and projectable into said opening, said arcuate bowed portion having ends normally disposed in advance of and toed in relative to the intermediate arcuate part of said bowed portion, and a clamping wheel rotatably mounted on said stud and adapted to be rotated in one direction for actuating said pad retaining member towards said pad whereby said ends initially grip the terminals of said pad and clamp said terminals against said rim and whereupon said intermediate arcuate part is subsequently on

further rotation of said wheel expanded to grip the intermediate part of said pad for clamping the latter against said rim.

17. An eyelash curler adapted to utilize a rubber pad, comprising; a frame, an arcuate brace secured to said frame, an actuator movably carried by said frame, an arcuate jaw disposed below said brace and comprising a pair of cooperating components, one of said components defining a pad sustaining member including a shelf for seating said pad and an upstanding arcuate rim, the other component of said pair defining a pad retaining member including an upstanding arcuate bowed portion disposed in advance of said pad sustaining member and having a depending portion embodying a clearing opening, means hingedly connecting said pad sustaining member to said actuator, means rotatably connecting said pad retaining member to said actuator, means slidably guiding said pad sustaining member relative to said frame, a threaded stud carried by one of said components and projectable into said opening, said arcuate bowed portion having ends and forwardly offset and depending lips normally disposed in advance of and toed in relative to the intermediate arcuate part of said bowed portion, and a clamping wheel rotatably mounted on said stud and adapted to be rotated in one direction for actuating said pad retaining member toward said pad whereby said ends and lips initially grip the terminals of said pad and clamp said terminals against said rim and whereupon said intermediate arcuate part is subsequently on further rotation of said wheel expanded to grip the intermediate part of said pad for clamping the latter against said rim.

18. The eyelash curler according to claim 4 wherein said rim embodies depending lip means adapted to be urged away from said guard for shifting said rim away from said guard.

19. The curler according to claim 18 characterized in that said rim embodies spaced lips extending below said shelf and straddling the apron of said sustaining member.

CHARLES M. PALMER.
